UNITED STATES PATENT OFFICE.

LARS O. GRONDAHL, OF PITTSBURGH, AND LEMUEL F. HOWARD, OF EDGEWOOD BOROUGH, PENNSYLVANIA, ASSIGNORS TO THE UNION SWITCH & SIGNAL COMPANY, OF SWISSVALE, PENNSYLVANIA, A CORPORATION OF PENNSYLVANIA.

RAILWAY SIGNALING.

Application filed April 16, 1921, Serial No. 461,750. Renewed May 18, 1923.

To all whom it may concern:

- Be it known that we, LARS O. GRONDAHL and LEMUEL F. HOWARD, citizens of the United States, residing at Pittsburgh and 5 Edgewood Borough, respectively, in the county of Allegheny and State of Pennsylvania, have invented certain new and useful Improvements in Railway Signaling, of which the following is a specification.
- 10 Our invention relates to railway signaling, and particularly to signaling of the type wherein roadside signals or other traffic governing devices are controlled by polarized track circuits.
- 15 We will describe two forms of signaling apparatus embodying our invention, and will then point out the novel features thereof in claims.

In the accompanying drawings, Fig. 1 is a 20 diagrammatic view showing one form of signaling apparatus embodying our invention, wherein the reversal of polarity of the track circuit current is accomplished by electromagnetic means. Fig. 2 is a view similar 25 to Fig. 1, except that the reversal of track circuit polarity is accomplished by light responsive cells.

Similar reference characters refer to similar parts in each of the views.

30 Referring first to Fig. 1, the reference characters 2 and 2^a designate the track rails of a railway along which traffic normally moves from right to left, as indicated by the arrow, and which rails are divided by insulated joints 3 to form a series of track sections A—B, B—C, etc.

Each track section is provided with a track circuit comprising a source of current and an electro-responsive device, the former 40 being connected across the rails at the exit end of the section, and the latter receiving current from the rails at the entrance end of the section. As here shown, the source of current for each section is the secondary 4 of a transformer which is designated by the reference character T with an exponent corresponding to the location. This secondary is connected across the rails through the medium of a polarity reversing device, as 45 hereinafter explained. The primary 5 of each transformer T is connected with transmission mains 6 to which alternating signal-

ing current is constantly supplied by a generator 7.

In Fig. 1 the reversal of track circuit polarity is accomplished by electromagnetic relays, each of which is designated by the reference character J with an exponent corresponding to the location. Each of these relays comprises a winding 55 and a pair of 55 pole-changing contacts 56 and 57. Considering relay J^B, for example, the winding 55 is connected across the rails of track section A—B, and the contacts of this relay control 60 the polarity of the current supplied to the track rails of section B—C from the secondary 4 of transformer T^B. When section A—B is unoccupied, relay J^B is energized and current of normal relative polarity is then supplied to section B—C; when section 70 A—B is occupied, however, relay J^B is de-energized, so that current of the other or reverse relative polarity is supplied to the rails of section B—C.

The electro-responsive device for each section is designated by the reference character E with an exponent corresponding to the location. As here shown, this device is a suspended coil galvanometer comprising fixed field coils 8 and 8^a, and a movable armature 80 coil 9. The armature coil 9 is connected directly across the track rails of the section, whereas the two field coils 8 and 8^a are connected in series across the terminals of a secondary 15 on the adjacent transformer T. It will be seen, therefore, that the field coils 85 are constantly energized by current of one relative polarity, whereas the armature coil 9 is energized by current of one relative polarity or the other when the track section is unoccupied, and is de-energized when the section is occupied. The parts are so arranged that when a track section such as B—C is occupied, the armature of the electro-responsive device E^C occupies a middle position to which it is biased; when current of reverse relative polarity is supplied to the rails of section B—C, the armature 9 swings to the right; and when current of normal relative polarity is supplied to section B—C, the armature swings to the left. Each of the other electro-responsive devices 95 operates in the same manner.

Located at the entrance end of each track

section are a source of light 12, and three light-responsive cells 13^c, 13^y and 13^r. The source of light 12, usually an electric incandescent lamp, is supplied with current from the adjacent transformer secondary 15 and is constantly lighted. Each light-responsive cell 13 has the characteristic of varying in electrical resistance in accordance with variations in the intensity of the light to which it is exposed. It may comprise a substance such as selenium, stibnite, or copper oxide, or it may be what is known as a photo-electric cell in which the active material is usually an alkali metal. The precise nature and form of these cells does not constitute any part of our present invention.

Attached to the armature 9 of each electro-responsive device E is a mirror 11, which is arranged to reflect a beam of light from the adjacent lamp 12 to the adjacent light-responsive cells 13^c, 13^y and 13^r. When the armature is in the middle position, the mirror reflects a beam of light from the lamp 12 to the light-responsive cell 13^r. When the armature moves to the left-hand extreme position, the mirror reflects a beam of light upon the cell 13^c, and when it moves to the right-hand extreme position, the mirror reflects a beam of light upon light-responsive cell 13^y.

Located adjacent the entrance end of each track section is a signal which is designated by the reference character S with an exponent corresponding to the location. Each signal in the form here shown comprises three electric lamps G, Y and R, which lamps, when lighted, indicate "proceed," "caution" and "stop," respectively. Referring to signal S^c, the circuit for the proceed lamp G is from the secondary 15 of transformer T^c, through wires 16, 17 and 18, lamp G, cell 13^c and wire 21 to the secondary 15. The circuit for the caution lamp Y is from secondary 15, through wires 16 and 20, lamp Y, cell 13^y, and wire 21 to the secondary 15. The circuit for the red lamp R is from secondary 15, through wires 16, 17 and 19, lamp R, light-responsive cell 13^r, and wire 21 to the secondary 15.

It will be seen from the foregoing, that the three lamps of each signal are connected in multiple across the terminals of secondary 15 of the adjacent transformer T, and that one of the light-responsive cells 13 is included in series with each lamp. The lamps and the cells are so proportioned that when any one of the cells is illuminated by a beam from lamp 12, the signal lamp which is in series with such cell will be lighted and the other signal lamps will be extinguished. This result may be accomplished because of the fact that the electrical resistance of each cell 13 is considerably lower when the cell is illuminated than when it is not. In order to obtain the proper current values it may

be found advantageous to interpose a transformer between each light-responsive cell and the corresponding lamp.

It will, of course, be understood that each cell 13 is protected in a suitable manner, so that the only rays of light which may reach the active material or substance of the cell are the rays which are projected by the mirror 11 from the source of light 12.

As shown in the drawing, track section A—B is occupied by a car or train W, so that the electro-responsive device E^b is de-energized. It follows that cell 13^r of signal S^b is illuminated so that lamp R of this signal is lighted and the signal indicates stop. Relay J^b is de-energized, so that current of reverse relative polarity is supplied to the rails of section B—C. Consequently, the armature 9 of the device E^c is swung to the right, so that light is thrown on the adjacent cell 13^y. Lamp Y of signal S^c is therefore lighted, so that this signal indicates caution. Relay J^c is energized, so that current of normal relative polarity is supplied to the rails of section C—D, and so it follows that light is thrown on the cell 13^c at location D. This causes lamp G of signal S^c to be lighted so that this signal indicates proceed.

Obviously, sources of direct current could be substituted for the transformers T in Fig. 1. If this substitution is made, no other change in the system is essential, but if desired, the electromagnetic devices E could be polarized by permanent magnets instead of by the field windings 8 and 8^a.

Referring now to Fig. 2, the apparatus shown herein is the same as that shown in Fig. 1 except as to the means for reversing the relative polarity of the current supplied to the track circuits. In Fig. 1 this is accomplished by a pole-changing relay having moving contacts, whereas in Fig. 2 it is accomplished by light-responsive cells and means for selectively illuminating such cells.

In Fig. 2 the pole-changing apparatus for each section is designated by the reference character K with an exponent corresponding to the location. Referring to the apparatus designated K^b, the electromagnetic device E^b is provided with an additional mirror 11^a, which throws rays from an additional lamp 12^a on light-responsive cells 70^r, 70^N and 70^{N_a}. When the electro-responsive device E^b is deenergized the middle cell 70^r is illuminated, and when the armature of the electromagnetic device is swung to the right or to the left, the right-hand cell 70^N or the left-hand cell 70^{N_a} is illuminated.

Current is supplied to the track rails of section B—C by a secondary 4 on transformer T^b as before. The middle point of this secondary is connected with the upper track rail 2 by a wire 58. The right-hand termi-

nal of secondary 4 is connected with the lower track rail 2^a by wires 59 and 60, light-responsive cell 70^N and wires 61 and 62. Cell 70^{N_a} is connected in multiple with cell 70^N by means of wires 63, 64 and 65. The left-hand terminal of secondary 4 is connected with the lower track rail 2^a by wire 67, cell 70^R, and wires 66, 65 and 62. Normally, therefore, the two outer terminals 10 of the secondary 4 are connected with the lower track rail through paths of comparatively high resistance. When light is thrown on the middle cell 70^R, however, the resistance between the left-hand terminal of 15 secondary 4 and the lower track rail is materially reduced, so that current of one relative polarity, which I will term reverse polarity, is supplied to the rails of the section B—C. When light is thrown on either 20 of the outer cells 70^N or 70^{N_a}, the resistance of the path between the right-hand terminal of secondary 4 and the lower track rail 2^a is materially reduced, so that current of the other or normal relative polarity is supplied to the track rails. On account of the 25 fact that light sensitive cells ordinarily have high resistances, it may be necessary in some instances to interpose a transformer between each pole-changer K and the track.

30 As shown in Fig. 2, track section A—B is occupied by a car or train W. The electro-responsive device E^B is therefore de-energized, so that signal S^B indicates stop. Cell 70^R in the pole-changing device K^B is illuminated, so that current of reverse polarity 35 is furnished to the rails of section B—C. Signal S^C indicates caution and cell 70^N of the pole-changing device K^C is illuminated. It follows that current of normal relative 40 polarity is supplied to section C—D so that signal S^D indicates proceed. In the pole-changing device K^D the left-hand cell 70^{N_a} is illuminated so that current of normal relative 45 polarity is supplied to the rails of the section to the right of location D.

In an application filed on even date herewith by L. O. Grondahl, Serial No. 461,782, filed April 16, 1921, there is shown in Fig. 5 an inductive type of electro-responsive device Q^c. A device of this type may be substituted for the devices E shown in the present application without any change in the circuits except that the third stator winding 50 74 would be eliminated and winding 71 would be connected across the track rails while winding 72 would be supplied with energy from a local source, such as a secondary of the adjacent transformer T.

Although we have herein shown and 55 described only a few forms of signaling apparatus embodying our invention, it is understood that various changes and modifications may be made therein within the scope of the appended claims without departing 60 from the spirit and scope of our invention.

Having thus described our invention, what we claim is:

1. In combination, a section of railway track, a track circuit for said section including a source of current reversibly connected with the rails and an electro-responsive device responsive to reversals of the connection of said source, two light-responsive cells, means controlled by said device for illuminating one cell or the other according 70 as said source is connected with the rails in one direction or the other, and a signal for said section controlled by said cells.

2. In combination, a section of railway track, means for supplying the rails of said section with current of normal or reverse polarity, a device for said section selectively responsive to the polarity of the current supplied to the rails, light-responsive cells, means controlled by said device for selectively illuminating said cells, and signaling means controlled by said cells.

3. In combination, a section of railway track, means for supplying the rails of said section with current of normal or reverse polarity, a device for said section selectively responsive to the polarity of the current supplied to the rails, two light-responsive cells, means controlled by said device for illuminating one of said cells or the other according 80 as current of normal or reverse polarity is supplied to the rails, and a signal controlled by said cells and arranged to indicate proceed or caution according as one cell or the other is illuminated.

4. In combination, a section of railway track, two circuits for supplying current of opposite polarities to the rails of said section, a light-responsive cell included in each circuit, and means controlled by traffic conditions in advance of said section for illuminating one or the other of said cells.

5. In combination, a section of railway track, two circuits for supplying current of opposite polarities to the rails of said section, a light-responsive cell included in each circuit, means controlled by traffic conditions in advance of said section for illuminating one or the other of said cells, a device for said section selectively responsive 105 to the polarity of the current in the rails, and a signal for said section controlled by said device.

6. In combination, a section of railway track, means including light-responsive cells for supplying current of different polarities to the rails of said section, and means for controlling the illumination of said cells by traffic conditions in advance of 120 said section.

7. In combination, a section of railway track, means for supplying the rails of said section with current of normal or reverse polarity, a device for said section selectively responsive to the polarity of the current 130

supplied to the rails, three light-responsive cells, means controlled by said device for illuminating the first or the second cell according as current of normal or reverse current is supplied to the device and the third cell when current is not supplied to the device, and a signal controlled by said cells and arranged to indicate proceed, caution or stop according as the first, second or 10 third cell is illuminated.

8. In combination, a section of railway

track, means for supplying the rails of said section with current of one polarity or the other, light-responsive cells, means responsive to the polarity of the current supplied to said rails for selectively illuminating said cells, and traffic governing means controlled by said cells.

In testimony whereof we affix our signatures.

LARS O. GRONDAHL.
LEMUEL F. HOWARD.
